UNITED STATES PATENT OFFICE.

JAMES O'NEIL, OF SAN FRANCISCO, CALIFORNIA.

DESIGN FOR CENTER-PIECE.

Specification forming part of Design No. 7,561, dated July 14, 1874; application filed June 12, 1874.
[Term of Patent 3½ years.]

CASE B.

To all whom it may concern:

Be it known that I, JAMES O'NEIL, of San Francisco, in the county of San Francisco and State of California, have invented or produced a new Design for Center-Pieces; and I do hereby declare that the following is a full, clear, and exact description of the same, reference being had to the annexed photographic illustration, and to the letters marked thereon.

This design consists of a rosette, *a*, from which extends radial arms of an architectural design, *b*, to the ends of which a knot, *c*, bound with two strings of ribbon, *d*, intersect and overlap each other, as shown. Between each two of the series of these knots is placed scroll-work *e*, and the whole surrounded by a lozen-

ged bead, *f*. From the lozenged bead extends an open-work scallop, consisting of shell-work *g* and scroll-work *h*, with alternate projecting mace *i* and figured ball *j*.

Having thus described my invention, what I claim as new, and desire to secure by Letters Patent, is—

The design for center-pieces, as set forth and described.

In witness whereof I have hereunto set my hand and seal.

JAMES O'NEIL. [L. S.]
